UNITED STATES PATENT OFFICE.

EUGENE H. SANDT, OF ALLENTOWN, PENNSYLVANIA.

DESIGN FOR A BRETZEL OR CRACKER.

SPECIFICATION forming part of Design No. 19,059, dated April 23, 1889.

Application filed March 30, 1889. Serial No. 305,467. Term of patent 7 years.

To all whom it may concern:

Be it known that I, EUGENE H. SANDT, a citizen of the United States, and a resident of Allentown, in the county of Lehigh and State 5 of Pennsylvania, have invented a certain new and useful Design for Bretzels; and I do declare the following to be a full, clear, and exact description of the invention, such as will enable others skilled in the art to which it applies to make and use the same, reference being had to the accompanying drawing, and to letters or figures of reference marked thereon, which form a part of this specification.

The figure of the drawing is a representation 15 of the design.

The design consists in the novel form and configuration of the cracker or bretzel, as hereinafter shown and described.

The cracker or bretzel is, with regard to its 20 exterior form, heart-shaped, and it has two lateral apertures, *a a*, the outer margins of which are concave, as at *b*, these concave margins being parallel to the convex curvatures *c* of the outer edge of the cracker. The inner 25 margins of these apertures *a a* are indented and form the edges of the twisted middle bar, *d*, the lower portion of which forms diverging branches *e e*, which join the lateral straight

portions *g g* of the cracker at right angles and form the upper angular marginal portion 30 of the diamond-shaped aperture *h*, the lower angular marginal portion of which is formed by the point *k* of the cracker, as shown. Curved terminal creases are provided at *l l* at the sides of the diamond-shaped lower portion, *m*, of the cracker, where said portion is joined by the curved lateral portions thereof, and opposite the points where the sides are joined by the diverging branches of the twisted middle bar which separates the three 35 apertures.

What I claim, and desire to secure by Letters Patent, is—

The design for crackers or bretzels, consisting of the heart-shaped exterior form having 45 the concave edge lateral apertures, the diamond-shaped aperture, and the twisted middle bar having the diverging branches separating the three apertures, as shown and described. 50

In testimony whereof I affix my signature in presence of two witnesses.

EUGENE H. SANDT.
